UNITED STATES PATENT OFFICE

158,873

FISH LURE OR SIMILAR ARTICLE

Seymour Kushner and Morris Kushner, Detroit,
Mich., assignors to Kushner Engineering Company, Detroit, Mich., a corporation of Michigan

Application September 30, 1948, Serial No. 148,886

Term of patent 14 years

(Cl. D31—4)

To all whom it may concern:

Be it known that we, Seymour Kushner and Morris Kushner, both citizens of the United States and residents of the city of Detroit, in the county of Wayne and State of Michigan, have jointly invented a new, original, and ornamental Design for a Fish Lure or Similar Article, of which the following is a specification, reference being had to the accompanying drawing, forming a part thereof.

On the drawing:

Figure 1 is a plan view of the fish lure or similar article, showing our new design; and

We claim:

The ornamental design for a fish lure or similar article, as shown.

SEYMOUR KUSHNER.
MORRIS KUSHNER.
